ALEXANDER WEINBERG, OF NEW YORK, N. Y.

GAME APPARATUS.

Application filed December 31, 1924. Serial No. 758,968.

To all whom it may concern:

Be it known that I, ALEXANDER WEINBERG, a citizen of the United States, and a resident of New York city, borough of Manhattan, county and State of New York, have invented a new and useful Game Apparatus, of which the following is a specification.

This invention relates to game apparatus.

An important object of the invention is to provide an apparatus, of the class mentioned, affording the playing of games which are entertaining and fascinating because of the spirit of competition afforded between participants and the skill required of the individual entrants.

Other objects of the invention will become apparent from the following description when taken in connection with the accompanying drawings in which—

20 Figure 1 is a plan view of the apparatus embodying my invention.

Figure 2 is a longitudinal sectional view taken on line 2—2 of Figure 1.

25 Figure 3 is a view in edge elevation showing the device folded into compact form as for shipment.

Figure 4 is a somewhat enlarged plan view of a ring retaining device.

30 Figure 5 is a sectional view taken on line 5—5 of Figure 4.

Figure 6 is a sectional view taken on line 6—6 of Figure 5.

35 Figure 7 is a view in elevation of a peg adapted to be employed in the keeping of score or scores made in one of the games afforded by the apparatus embodying my invention.

40 In the drawings wherein for the purpose of illustration is shown what I at present consider the preferred form of my invention, the numeral 5 indicates a base to which is hingedly connected a peg-retaining support 6. This support is provided with a substantially semi-circular baffle or abutment 7, suitably secured in position and carries a plurality of pegs or posts 8. The support is so hinged to the base 5 by means of a fabric strip 9 or the like carrying a spacing element 10 that the support together with the baffle element 7 may be so folded over upon the base 5, as shown in Figure 3, as to house or enclose the pegs 8 thus protecting the same against injury in shipping or storing the apparatus as will be readily appreciated.

When playing the game or games here-

inafter more particularly described the support 6 is so positioned with respect to the base 5 as to assume an angle with respect thereto and is retained properly positioned by means of an anchoring cord 11. In order to meet certain requirements in the playing of the game depending, possibly, on the skill of the participants, it becomes desirable to provide for different adjustments of the support 6 with respect to the base 5 and to this end the anchoring cord 11 makes such variations possible. In this connection it will be noted that the cord 11 is attached to the support 6 at one side thereof by slipping one end of the cord into an opening 12 through a communicating slot 12', the cord being provided with a knot 13 to prevent displacement thereof. The cord is then passed into a similar opening 14 through a communicating slot 14' formed at one side of the base 5 the cord extending across the base at the underneath side thereof and up through an opening 15 which also communicates with a slot 15' whereupon the cord is then passed or looped through a pair of openings 16 and 17 communicating respectively with slots 16' and 17' formed in the support 6. It will, therefore, appear that in order to adjust the support 6 to a greater or less degree, as desired, it becomes necessary only to correspondingly draw the free end 18 of the cord through the openings 16 and 17 in one direction or the other. Upon making such adjustment the length of the cord between its points of connection with the support 6 is effectively shortened or lengthened, as the case may be, sufficient friction being maintained between the support 6 and the cord 11 at its free end to retain the support in a desired position.

To the rear of the base 5 there is pivotally connected a ring retaining and positioning device indicated as a whole by the numeral 19. This device is preferably constructed from sheet metal and comprises a base plate 20 secured to the base 5 by means of a rivet 21, the base being slotted, as shown at 22, to provide a pair of upstanding flanges 23 adapted to receive therebetween a ring 24. To the base plate 20 there is suitably connected a bridge member 25 comprising a pair of inclined sides 26 and 27 both of which are slotted to provide pairs of depending flanges or positioning elements 28 and 29 respectively, between which the ring 24 is adapted to be positioned. Although

the bridge member 25 may be secured to the base plate 20 in various ways, I have, in this instance, shown the sides 26 and 27 as provided respectively with lugs or ears 30 and 31 which are passed through suitable openings 32 formed in the base plate, the lugs or ears being bent over upon the under face of the base plate 20, as shown most clearly in Figures 4 and 5, thereby locking the bridge firmly in position. The base plate 20 is provided with a graduation or pointer, indicated by the numeral 33, whereas the base 5 is provided with a series of graduations 34. In this connection it may be pointed out that one in executing a play may elect to direct the ring toward a given or selected peg in which case the graduations may be, as will be readily appreciated, found helpful in enabling one to properly direct the ring toward the selected objective.

One of the games made possible by the apparatus embodying my invention may be described as follows: Assuming that two participants desire to play the game about to be described, a given number of rings are allotted to each player. The first player places a ring allotted to him in the retaining device 19, as shown in Figure 5, and with his forefinger positioned, as shown in Figure 1, imparts a blow to the ring thereby directing it toward the group of pegs 8. The ring so directed may be baffled around into the group of pegs by means of the baffle or abutment 7 or it may enter the group directly. If the ring comes to rest about any one of the pegs other than the center ring a score of one point is counted in favor of the player. The participant continues to discharge the rings from the retaining device until he has consumed the total number of rings allotted to him and for each ring that comes to rest about a peg, other than the central peg, a score of one is recorded in his favor, as above explained. Ringing of the central peg, however, entitles the participant to an additional score of five points for each time that the ring comes to rest about the central peg. After the first participant has executed his several plays, the following person or persons execute their plays in order, as above described the score for each participant being kept separately from that of the others. The game may be concluded after each player has had one, two or as many turns as may be decided upon at the outset. At the end of the game the respective scores are added and the participant having the highest score is deemed the winner of the contest. For each ring, however, that a participant lodges in one of the circles indicated by the numeral 35, a certain number of points may be deducted from his total score at the conclusion of the game. For example, if a ring lodges in either of the central circles, two points may

be deducted, whereas if a ring lodges in either of the outermost circles one point may be deducted. These deductions may be considered as minus scores which, when added at the conclusion of the game, are, as above mentioned, deducted from the total score of the respective individuals who have been so unfortunate as to fail to escape the penalty.

Another game made possible by the apparatus embodying my invention may be briefly described as follows. A column of figures, such as those appearing at the rear of the base 5 in Figure 1, is allotted to each participant together with a prescribed number of rings. The participants then in turn execute their plays directing their rings successively into the group of pegs 8. If a peg, bearing a number corresponding to a number found in the column of figures allotted to the particular participant, is rung, a pin such as is indicated by the numeral 36 is thereupon inserted into the opening formed in the base 5 adjacent the number corresponding to the peg just rung, the openings in the base being indicated by the numeral 37. After the first participant executes all of his plays the remaining participants, in order, execute their respective plays. The scoring is carried out in each case as above mentioned and the participant first filling the group of openings 37 of his particular column is deemed winner of the contest. Other rules, of course, governing the game may be taken into consideration, if deemed desirable, such for example, as penalties and so on which need no discussion in so far as the present disclosure is concerned.

While I have shown the apparatus as designed for use in the home, in which case the rings are propelled by one's finger, it will be readily understood that the apparatus lends itself to use in amusement parks, and the like, without departing from the spirit of the invention. If the apparatus were used as an amusement park device, it would be constructed on a much larger scale than otherwise, thus requiring the use of a mallet or similar instrument as a means for propelling the rings in executing the plays hereinbefore described.

I claim:

1. In a game apparatus, a base, a peg retaining support having a plurality of pegs carried thereby and projecting therefrom at an angle with respect to said base and a ring retaining device adapted for the reception of a ring to be propelled in the direction of said pegs, said ring retaining device being pivotally connected to said base whereby the device may be adjusted to various angles with respect to a plane passing longitudinally through said base.

2. In a game apparatus, a base, a peg retaining support hingedly connected to said base and having a plurality of pegs asso-

ciated therewith and projecting therefrom at an angle with respect to said base and a ring retaining device adapted for the reception of a ring to be propelled in the direction of said pegs.

3. In a game apparatus, a base, a peg retaining support hingedly connected to said base and having a plurality of pegs associated therewith and projecting therefrom at an angle with respect to said base and a ring retaining device adapted for the reception of a ring to be propelled in the direction of said pegs, said ring retaining device being pivotally connected to said base whereby said device may be angularly adjusted with respect to a plane passing longitudinally through said base.

4. In a game apparatus, a base, a peg retaining support hingedly connected to said base and adapted for angular adjustment with respect to said base, said peg retaining support being provided with a group of pegs, means for retaining said peg retaining support in a given adjusted position with respect to said base and a ring retaining device associated with said base and adapted for the reception of a ring to be propelled in the direction of said group of pegs.

5. In a game apparatus, a base, a peg retaining support hingedly connected to said base and adapted to be adjusted to various angles with respect thereto, means for retaining said support in a given adjusted position with respect to said base, said means being in the form of a flexible member associated with said base and having one end slidably connected to said support and a ring retaining device associated with said base and adapted for the reception of a ring to be propelled in the direction of said group of pegs.

6. In a game apparatus, a base, a peg retaining support hingedly connected to said base and adapted to be adjusted to various angular positions with respect to said base, a group of pegs associated with said support, means for retaining said support in a given adjusted position, said means being in the form of a flexible element having one end anchored to said support and its opposite end slidably connected with said support, said flexible element being intermediate its ends slidably connected to said base and a ring retaining device associated with said base adapted for the reception of a ring to be propelled in the direction of said group of pegs.

7. In a game apparatus, a base, a peg retaining support hingedly connected to said base and adapted to assume various angles with respect to said base, a group of pegs carried by said support, a ring retaining device pivotally connected to said base and adapted for the reception of a ring

to be propelled in the direction of said group of pegs and a baffling element partially encircling said group of pegs for deflecting the propelled ring into said group of pegs.

8. In a game apparatus, a base, a peg retaining support associated with said base and carrying a peg, a retaining device adapted for the reception of a ring to be discharged therefrom and propelled in the direction of said peg, said ring retaining device comprising a slotted element into which the ring is adapted to be positioned and retained in a vertical position prior to its being discharged.

9. In a game apparatus, a base, a peg retaining support associated with said base and carrying a peg, a ring retaining device adapted for the reception of a ring to be discharged therefrom and propelled in the direction of said peg, said ring retaining device comprising a bridge element having a slot formed therein wherein the ring is adapted to be positioned and retained in a vertical position prior to its being discharged.

10. In a game apparatus, a base, a peg retaining support associated with said base and carrying a peg, a ring retaining device adapted for the reception of a ring to be discharged therefrom and propelled in the direction of said peg, said ring retaining device comprising a base plate pivotally connected to said base, a bridge member secured to said base plate and provided with a slot into which said ring is adapted to be positioned and within which said ring is adapted to be retained in a vertical position prior to its being discharged.

11. In a game apparatus, a base, a peg retaining support associated with said base and carrying a peg, a ring retaining device adapted for the reception of a ring to be discharged therefrom and propelled in the direction of said peg, said ring retaining device comprising a base plate provided with a pair of upstanding flanges spaced from each other, a bridge member secured to said base plate and provided with a slot, said slot and the space afforded between said flanges being adapted for the reception and retention of a ring in a vertical position prior to its being discharged.

12. In a game apparatus, a base, a peg retaining support associated with said base and carrying a peg, a ring retaining device adapted for the reception of a ring to be discharged therefrom and propelled in the direction of said peg, said ring retaining device comprising a base plate provided with a pair of upstanding flanges spaced from each other, a bridge member secured to said base plate and provided with a slot, said slot and the space afforded between said flanges being adapted for the reception and retention of a ring in a vertical position prior to its being discharged.

tion and retention of a ring in a vertical position prior to its being discharged and guide flanges carried by said bridge member upon opposite sides of said slot to guide 5 said ring as it is discharged from said ring retaining device.

13. In a game apparatus, a base, a peg retaining support associated with said base and carrying a peg, and ring retaining 10 means adapted to retain a ring in standing

position to be rolled in the direction of said peg, said ring retaining means comprising spaced positioning elements between which said ring is adapted to be inserted and by which said ring is adapted to be retained in a standing position prior to its being rolled in the direction of said peg. 15

In testimony whereof, I have affixed my signature to this specification.

ALEXANDER WEINBERG.
